THE NORRIS PETERS CO., PHOTO-LITHO., WASHINGTON, D. C.

UNITED STATES PATENT OFFICE.

ISAAC NEWTON BUNDREN, OF NEW CAMBRIA, MISSOURI.

PRESSING DEVICE.

SPECIFICATION forming part of Letters Patent No. 588,125, dated August 17, 1897.

Application filed March 31, 1897. Serial No. 630,163. (No model.)

To all whom it may concern:

Be it known that I, ISAAC NEWTON BUNDREN, a citizen of the United States, residing at New Cambria, in the county of Macon and State of Missouri, have invented a new and useful Pressing Device, of which the following is a specification.

This invention relates to certain improvements in devices such as are especially adapted for pressing sacks of flour, meal, &c., into a flattened condition suitable for close packing or piling up; and the object of the invention is to provide a device of this character of a simple and inexpensive nature which shall be adapted to operate in a substantially automatic manner to press the sacks of flour into the required flattened condition.

The invention consists in a device of this character comprising a frame, a platform on the frame whereon the sack of flour or other article to be compressed is adapted to be supported, a compressing device carried on the frame over the platform, and means for moving said parts relatively to each other to cause the platform to pass under the compressing device in order that the article supported on the platform may be pressed into a flattened condition.

The invention also contemplates certain novel features of the construction, arrangement, and combination of the various parts of the improved device whereby certain important advantages are attained, and the device is made simpler, cheaper, and otherwise better adapted and more convenient for use, all as will be hereinafter fully set forth.

The novel features of the invention will be carefully defined in the claims.

In order that my improvements may be better understood, I have shown in the accompanying drawings a pressing device constructed according to my invention, in which—

Figure 1 is a perspective view of the pressing device, showing a sack of flour or other article to be pressed supported upon the platform. Fig. 2 is a vertical sectional view taken longitudinally through the device. Fig. 3 is a partial sectional view similar to Fig. 2, but showing the reverse position of the sack-supporting platform. Fig. 4 is a vertical section taken transversely through the device in the

plane indicated by the line *a a* in Fig. 3. Fig. 5 is a partial side view showing the side of the machine opposite to that seen in Fig. 1. 55

The frame of the improved device is formed with a base portion 1, from which extend upward standards 2 2, located at the several corners and at the central part of the base 1, which is, as seen in the drawings, of rectangular form, and said standards 2 support adjacent to their upper ends parallel tracks 3 3, arranged longitudinally of the machine and secured by means of bolts or other devices to the inner surfaces of the supporting-stands 2 of the frame, as clearly shown in Figs. 1 and 4. The frame of the device is also constructed with parallel side bars 4 4, extending along opposite sides of its upper part, its side bars being located above and outside of 70 the tracks 3, with which they are parallel, and being adapted to guide the sack-supporting platform, which moves along said tracks 3, whereby said platform is held against lateral movement. 75

The platform is constructed with a frame 5, of rectangular form, having on its under side axles 6, extending transversely across it and secured thereto in any preferred way, which axles are provided at their extremities 80 beyond the sides of the frame 5 with track wheels or rollers 7, arranged to run upon the tracks 3. The frame 5 carries upon its upper part the platform proper, which is, as shown clearly in the sectional view Fig. 4, formed 85 of parallel side portions 8 8, spaced apart to form an opening between them, wherein plays a vertically-movable section or part 9, extending longitudinally of the platform and adapted to be depressed by the weight of the sack 90 of flour or other article deposited upon the platform, as shown in Fig. 2, said vertically-movable section or part 9 standing, when depressed, substantially level with the side portions 8 8 of the platform and being provided 95 at suitable intervals with rods or stems 10, projecting down from its under side and passing through openings formed in the cross-pieces of the frame 5, by means of which stems or rods the movable section or part 9 is guided. 100

The cross-pieces of the frame 5, through which the stems or rods 10 pass, are recessed at their upper parts, as shown at 11, to permit the introduction of springs 12, coiled upon

the upper portions of said rods or stems and bearing at their lower ends upon the bottoms of said recesses in such a way as to hold the movable section or part 9 of the platform normally in its raised position, and the lower ends of said stems or rods 10 extend down below the under side of the frame 5 and are connected with a beam 13, which extends longitudinally along the under side of the frame 10 between and at a slight distance below the treads of the track wheels or rollers 7, as shown in Fig. 4.

On the under side of the beam 13 is secured a rack-bar 14, having teeth formed in its under side, as clearly shown in Figs. 2 and 3, and the teeth of said rack-bar are adapted, as the movable section or part 9 of the platform moves up and down, to be engaged with and disengaged from the teeth of a pinion 15, carried on a shaft 16, extending across the frame of the device between the tracks 3 3, and one end of said shaft 16 extends outside of the frame of the machine and is provided with a pulley 17, adapted for the passage of 25 a driving-belt 18, by means of which the device is adapted to be driven from any suitable source of power.

On the extremity of the shaft 16, opposite to the pulley 17, is fixed a sprocket-wheel 19, over which passes a sprocket-chain or link belt 20, extending down and around a sprocket-wheel 22, carried on a bearing-stud 23, secured to the side of the frame beneath the shaft 16, and said sprocket-chain 20 extends 35 up, as shown in the drawings, and over a sprocket-wheel 24, fixed on the end of a shaft 25, extending transversely across the frame and having its ends supported in bearing-blocks 26, mounted for vertical adjustment 40 on brackets 27, secured to and extending above the side bars 4 of the frame. The brackets 27 are, as shown in the drawings, formed of metal rods or bars bent to a V shape and having their opposite end portions carried down and secured to the upper surfaces of the side bars 4, and one of the sides of each bracket is arranged vertically and is adapted for the vertical movement of the bearing-block 27 at that end of the shaft 25. 45 The bearing-stud 23, whereon the sprocket-wheel 22 is carried, is likewise adapted for vertical adjustment, being provided with a shank extending through a slotted opening 28 in a bracket 29, secured to one of the standards 2 of the frame and provided with a nut 30, screwing upon it, by means of which said bearing-stud is secured to the frame of the device when properly adjusted. On the shaft 25, between the bearing-blocks 26, wherein 50 the same turns, is arranged a compressing-roller 31, which is adapted to pass over the upper part of the sack of flour or other article to be pressed when the same is upon the platform, and by means of the adjusting devices above described it will be seen that said roller may be adjusted up and down upon the frame, so as to stand nearer to or farther from

the platform whereon the sack of flour or other article is supported, and by this means the device is made adjustable, so as to be adapted 70 for pressing bags of different sizes and containing material of different kinds.

At the central portion of the frame of the device is arranged a boxing 32, forming within it a vertical well or channel wherein is arranged to play a weight 33, carried on the end of a cord or chain 34, extending over a pulley 35 at the upper end of said well or channel, said cord or chain being connected at its upper end to the forward portion of the platform, such connection being, as shown in the drawings, made with the forward portion of the beam 13 at the under side of said platform, and by this arrangement it will be seen that said weight is caused to hold the platform 80 normally drawn over toward one end of the tracks 3, as shown in Fig. 1, the said track being for this reason provided with stops 36, projecting up into the path of the track wheels or rollers 11 in such a way as to prevent 90 the said track wheels or rollers from being disengaged from the extremities of the tracks.

In operation the belt 18 will be employed to continuously drive the shaft 16, whereon the pinion 15 is secured, and it will be seen 95 that when no sack is upon the platform of the device the movable part or section 9 of the platform will stand in its raised position, as shown in Fig. 3, so as to hold the rack-bar 14 out of engagement with said pinion 15, but when a sack of flour or other article to be 100 pressed is deposited upon the platform of the device the weight of said sack will serve to depress the movable part or section 9 of the platform so as to engage the teeth of the rack-bar with the pinion 15, whereupon the 105 rotative movement of said pinion will act to move the rack-bar 14 and the platform to which the same is connected endwise in the direction of the arrow in Fig. 1, so as to cause the sack of 110 flour (indicated at y) to pass beneath the compressing-roller 31, by means of which it will be pressed into a flattened condition suitable for piling up.

The endwise movement of the platform 115 whereon the sack of flour or other article is carried relative to the frame of the device will serve to cause the sack to pass completely under the compressing-roller 31, and the rack-bar 14 is of such length that after the platform 120 has been moved in the direction of the arrow to its fullest extent, as shown in dotted lines in Fig. 2, the platform whereon said rack-bar is carried will be held in position with the sack of flour or other article thereon 125 out of contact with the compressing-roller 31, so that said sack may be conveniently removed from the platform.

By the endwise movement of the sack-supporting platform relative to the frame it will 130 be seen that the weight 33 will be caused to rise in the well or channel 32, and after the sack of flour or other article has been removed from the platform, so as to permit the mov-

able part or section 9 thereof to rise vertically in such a way as to disengage the rack-bar 14, connected to said movable section, from the pinion 15, said weight 33 will be 5 permitted to act to return the platform to its first position, as indicated in full lines in Fig. 2, ready to receive another sack of flour to be pressed, the rack-bar when raised passing back directly over, but out of engagement 10 with, the teeth of the pinion 15, as will be readily understood.

From the above description it will be seen that the improved device is of an extremely simple and inexpensive construction and permits 15 the sacks of flour or other articles to be pressed into a flattened condition in a substantially automatic manner, and it will also be seen that the invention is susceptible of some modification without material departure 20 from its principles and spirit, and for this reason I do not wish to be understood as limiting myself to the precise form and arrangement of the several parts herein set forth.

What I claim is—

25 1. In a device of the character described, the combination of a frame, a platform arranged on the frame and adapted to receive an article to be pressed, a compressing device mounted on the frame and located above the 30 platform, and means for moving the parts relatively to each other to cause the platform to pass under the compressing device automatically when an article is placed upon the said platform, substantially as described.

35 2. In a device of the character described, the combination of a frame, a platform on the frame whereon the article to be pressed is adapted to be supported, a compressing device mounted on the frame and located above 40 the platform, and means for moving the parts relatively to each other to cause the platform to pass beneath the compressing device, said means being controlled by the article carried on the platform, substantially as set forth.

45 3. In a device of the character described, the combination of a frame, a platform on the frame whereon the article to be pressed is adapted to be supported, a compressing device carried on the frame over the platform, 50 actuating devices for moving the parts relatively to each other to cause the platform to pass beneath the compressing device, and controlling mechanism for said actuating devices, said controlling mechanism being carried by the platform and being controlled by 55 the article supported thereon, substantially as set forth.

60 4. In a device of the character described, the combination of a frame, a platform on the frame whereon the article to be pressed is adapted to be supported, a compressing device carried on the frame over the platform, actuating devices for moving said parts relatively to each other to cause the platform to 65 pass in one direction under the compressing device, means for retracting the parts, and controlling mechanism for said actuating de-

vices, said controlling mechanism being carried on the platform and controlled by the article supported thereon, substantially as set forth.

5. In a device of the character described, the combination of a frame, a platform movable along the same, a pressing device on the frame over the platform, actuating devices to 75 move the platform to cause the article carried thereon to pass under the pressing device, and controlling mechanism for said actuating devices, said mechanism being controlled by the article on the platform, substantially as 80 set forth.

6. In a device of the character described, the combination of a frame, a platform movable along the same, a pressing device on the frame, actuating devices to move the platform to cause the article carried thereon to 85 pass under the pressing device, said devices comprising engaging parts carried respectively by the frame and platform and normally held out of engagement, and means actuated by the article supported on the platform to move said parts into engagement, substantially as set forth.

7. In a device of the character described, the combination of a frame, a platform movable along the same, a pressing device on the frame, gearing to move the platform to cause the article on the platform to pass under the pressing device, said gearing comprising gears carried respectively on the 95 platform and frame and normally held out of engagement, and means actuated by the article on the platform to throw the gears into engagement, substantially as set forth.

8. In a device of the character described, 105 the combination of a frame, a platform movable along the frame, a pressing device on the frame, rack and pinion gearing for moving the platform to cause the article to be pressed to pass under the pressing device, one element of 110 said gearing being mounted on the frame and the other element being mounted on the platform, said gearing being normally out of engagement, and means for throwing the gearing into engagement, substantially as set 115 forth.

9. In a device of the character described, the combination of a frame, a platform movable along the frame, a pressing device on the frame, actuating devices to move the platform to cause the article thereon to pass under the pressing device, and a movable part on 120 said platform to be moved by the article placed on the platform, said movable part being arranged to control said actuating devices, substantially as set forth.

10. In a device of the character described, the combination of a frame, a platform movable along the frame, a pressing device on the frame, actuating devices to move the platform to cause the article thereon to pass under the pressing device, and a spring-supported part on said platform adapted to be depressed by the article thereon, and ar-

ranged to control said actuating devices, substantially as set forth.

11. In a device of the character described, the combination of a frame, a platform movable along the frame, a pressing device on the frame, and actuating devices to move the platform in one direction to cause the article on the platform to pass under the pressing device, said actuating devices being held in operative position by the weight of the article on the platform, substantially as set forth.

12. In a device of the character described, the combination of a frame, a platform movable thereon, a pressing device on the frame, actuating devices to move the platform in one direction to cause the article thereon to pass under the pressing device, said actuating devices being held in operative position by the weight of the article on the platform, and means to move the platform in the opposite direction when the article is removed therefrom, substantially as set forth.

13. In a device of the character described, the combination of a frame, a platform movable thereon, a pressing device on the frame, actuating devices to move the platform in one direction to cause the article thereon to pass under the pressing device, said actuating devices being held in operative position by the article placed on the platform, and a weight connected with the platform to retract the same when the article is removed therefrom, substantially as set forth.

14. In a device of the character described, the combination of a frame, a platform movable thereon, a pressing device on the frame, a rotative shaft on the frame and provided with a pinion, a rack-bar movable on the platform and arranged when moved in one direction to engage said pinion to move the platform to cause the article thereon to pass under the pressing device, and a spring-actuated part on the platform to be moved by the article on the platform, said part being connected to the rack-bar and adapted to move the same

into and out of engagement with the pinion, substantially as set forth.

15. In a device of the character described, the combination of a frame, tracks extending on the same, a platform having wheels engaging the tracks, actuating devices controlled by the article placed on the platform to move the platform along the tracks, and a pressing device supported on the frame over the tracks, beneath which pressing device the article on the platform is arranged to pass, substantially as set forth.

16. In a device of the character described, the combination of a frame, a pressing device thereon, a platform movable on the frame, and adapted to carry an article to be pressed, a rotative shaft on the frame, a pinion on the shaft, a rack movable into and out of engagement with the pinion, a movable part on the platform, to be moved by the article placed thereon, stems connecting the said part with the rack-bar, and springs for holding said part and the rack-bar normally out of operative position, substantially as set forth.

17. In a device of the character described, the combination of a frame, a platform movable on the same and adapted to carry an article to be pressed, a shaft rotatively mounted over the path of the platform and adjustable toward the same, a compressing-roller on the shaft, a bearing-stud also adjustable in the same direction as the said shaft, means to move the platform, an endless driving-belt connecting the said shaft and bearing-stud, and a driving device engaging the intermediate part of said belt to drive the same, substantially as set forth.

In testimony that I claim the foregoing as my own I have hereto affixed my signature in the presence of two witnesses.

ISAAC NEWTON BUNDREN.
